FIG. 2.

FIG. 3.

UNITED STATES PATENT OFFICE

2,534,380

GARMENT BAG

Nathan L. Schwartzman, Jersey City, N. J., assignor to Protex Products Company, Jersey City, N. J., a corporation

Application August 8, 1947, Serial No. 767,405

1 Claim (Cl. 312—3)

1.

This invention relates to garment bags adapted to contain and protect clothing. More particularly, this invention is concerned with garment bags formed of plastic or other sheet materials.

An object of this invention is to provide a garment bag of the character described which comprises plastic sheet material. The plastic sheet material is provided in the form of a single blank which may be folded and seamed to produce a structure of rectangular cross-section and further includes a combination garment supporting means and hanger means.

A further object of this invention is to provide a blank of plastic sheet material which comprises cut out corner sections and cut out portions on edges intermediate the corners whereby the blank may be folded to produce a bag structure of rectangular cross section and having a minimum number of abutting edges to be seamed to produce such a structure.

Still another object of this invention is to provide a blank of plastic sheet material which has cut out portions thereby permitting the blank to be folded into a bag structure and including a zipper type closure strip wherein a minimum amount of seaming operations are necessary.

Another object of this invention is to provide a compact, durable garment bag of the character described, which shall be relatively inexpensive to manufacture, easy to assemble and yet practical and efficient to a high degree in use.

Other objects of this invention will in part be obvious and part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown various possible illustrative embodiments of this invention,

Fig. 1 is a perspective view of the garment bag embodying the invention;

Fig. 2 is a perspective view of the upper portion of the bag shown in Fig. 1, with parts broken away;

Fig. 3 is a perspective view of a blank which may be used in forming the bag shown in Fig. 1;

Fig. 4 is a perspective view of a portion of a blank similar to that shown in Fig. 3 and illustrating a modified construction;

Fig. 5 is a cross-sectional view taken on the line 5—5 of Fig. 2;

2.

Fig. 6 is a cross-sectional view taken on the line 6—6 of Fig. 1;

Fig. 7 is a cross-sectional view taken on the line 7—7 of Fig. 1;

Fig. 8 is a cross-sectional view taken on the line 8—8 of Fig. 1; and

Fig. 9 is a cross-sectional view taken on the line 9—9 of Fig. 1.

Referring now in detail to the drawing, 10 designates a bag structure embodying the invention. The same may be made from a blank 11 such as shown in Fig. 3. The blank 11, which may be made of sheet material such as thermoplastic film, paper, fabric, or the like, comprises a pair of similar panels or walls 12, 13 of generally rectangular shape. Each panel is formed with rectangular cut out corners 14, 15, 16, 17. The panels 12, 13 are then provided with upper and lower flaps 18, 19 and side flaps 20, 21.

15 The panels 12 and 13 are joined together along the longitudinal edge portions 22 of the side flaps 21. The edge portions 22 of the blanks are turned inwardly and seamed in abutting relationship by means of solvent cement, hot welding, sewing or combinations thereof.

20 The blank 11 thus formed is folded to form the bag 10. To this end, the flaps 18, 19 and 20 are folded inwardly on lines connecting the corners of the cut out portions 17, 14; 14, 15 and 15, 16, respectively. The seamed flap portions 21 are also folded along a line connecting the corners of the cut out portions 16, 17 of the panels. The folding operations bring the edges of the corresponding flaps 18 and 19 into substantially abutting relationship. The dimensions of the flaps 18, 19 are such as to permit the edge portions 18a, 19a thereof, respectively, to be inwardly turned and seamed in abutting relationship as shown in Fig. 7.

25 Similarly, the edges 14a, 14b of the corner cut out portion 14 and the edges 15a, 15b of the corner cut out portion 15 are brought into abutting relationship and seamed in the manner previously described. To reinforce the seams a folded

30 strip 23 may be placed over the seams and secured thereto by stitching 24. The flaps 20 thus form the front wall of the bag structure 10 as shown in Fig. 1.

35 The edges 17a, 17b of the corner cut out portion 17 and the edges 16a, 16b of the corner cut out portion 16 are also brought into abutting relationship and seamed. The flaps 21 will then form the back end of the bag structure while the flaps 18 form the top and the flaps 19 form the bottom thereof.

The width of the flaps 20 is such as to provide a longitudinal space therebetween when the flaps are in folded form. The edges of the flaps 20 are interconnected by a longitudinally extending closure strip 25 which comprises a tape 26 having outer edges 27. The edges 27 of the tape 26 are superposed over the outwardly turned edges 28 of the flaps 20. A folded reenforcing strip 29 enfolds the superposed tape edge and flap edge and is secured thereto by stitching 30. The upper and lower edges of the tape 26 are seamed to the edges of the upper and lower flaps. The tape 26 also comprises interengaging elements secured to the inner edges thereof and forming a slide fastener or zipper closure 32. The closure portion of the strip may extend from the top of the bag to a point short of the bottom thereof as shown in Fig. 1. A pair of loops 31 of fabric, plastic or the like may be interposed between the seamed edge portions of the tape 26 and the flap edges 28 and are positioned at the upper and lower ends of the closure tape 25 as shown in Fig. 1, for the purpose hereinafter appearing.

The bag 10 is provided with a rectangular wire frame 33 which extends about the peripheral portions of the top portion of the bag. The frame 33 comprises a pair of side members 34 which are interconnected at their mid portions by a corrugated member 35. A pair of collars 36 are mounted on spaced portions of the member 35. The collars 36 are formed with openings 37 which receive the lower end of hook members 38, in engaging relationship thereto as shown in Fig. 5. The flaps 18 of the bag 10 are formed with openings 39 opposite the collars 36 and are reenforced by a tab 40 and a grommet 41. The hooks 38 pass through the reinforced openings 39 in flaps 18.

It will be apparent that the corrugated member 35 mounted on the frame 33 forms supporting means for garments suspended within the bag. The hooks 38 extending outwardly from the corrugated member and projecting through the top of the bag, permit the suspension of the bag as a whole from suitable suspending means.

A stiffening and shaping member 42 such as cardboard or the like may be inserted in the bottom portion of the bag.

In Fig. 4 is shown a blank 11a which is similar to that shown in Fig. 3 except that it is in the form of a single piece. The blank 11a is provided with the cut out corner portions similarly disposed, as shown in Fig. 3. The blank 11a is folded and the edge portions thereof seamed in the same manner as previously described. It will be apparent that the blank 11a may be used when wide stock is available, thereby eliminating the need for seaming two panels as shown in Fig. 3.

The loops 31 are used to facilitate the operation of the zipper closure. The upper being grasped when opening the bag and the lower is grasped when the bag is to be closed.

It will thus be seen that there is provided a device in which the several objects of this invention are achieved, and which is well adapted to meet the conditions of practical use.

As various possible embodiments might be made of the above invention, and as various changes might be made in the embodiment above set forth or shown in the accompanying drawing is to be interpreted as illustrative and not in a limiting sense.

Having thus described my invention I claim as new and desire to secure by Letters Patent:

A garment bag formed of thin transparent sheet material and having side walls connected by a rear wall integral with rear edges of the side walls, said side walls having upper and lower portions projecting beyond ends of the rear wall and folded inwardly and forming flaps extending towards each other and secured together along their inner meeting edges to form upper and lower end walls having rear edges secured along the upper and lower edges of said rear wall, said side walls having portions projecting forwardly from the upper and lower flaps even with the upper and lower edges of the rear wall and folded inwardly and forming side sections of a front wall, the said front wall sections having upper and lower edges secured along front edges of the upper and lower end walls and their inner side edges spaced from each other and defining a vertically extending front opening midway the width of the front wall, a closure for the front opening consisting of a longitudinally slit tape disposed vertically between the side sections and secured along its edges to the inner side edges of the said side sections, slide fastener actuated means to close said slit, and a frame fitting in the bag against the upper end wall and carrying support-engaging hooks extending upwardly and out of the bag through openings in the upper wall.

NATHAN L. SCHWARTZMAN.
